UNITED STATES PATENT OFFICE.

FRANZ ERNST WILHELM MÖLLER, OF ADELAIDE, SOUTH AUSTRALIA, AUSTRALIA.

FOOTWEAR.

1,166,239.

Specification of Letters Patent.

Patented Dec. 28, 1915.

Application filed January 31, 1914. Serial No. 815,789.

To all whom it may concern:

Be it known that I, FRANZ ERNST WILHELM MÖLLER, a subject of the King of Great Britain, residing at 199 Rundle street, 5 Adelaide, South Australia, Australia, have invented new and useful Improvements in Footwear, of which the following is a specification.

This invention relates to improvements in 10 footwear and has to do more especially with attachment of removable or false wearing surfaces.

One object of the invention is to provide means whereby the wearing portions of the 15 heels and soles of boots can be removed and replaced without necessitating the use of nails, brads or stitches.

Another object is to provide a heel member which is interchangeable and is rotatably 20 mounted so that inequalities of wear may be readily adjusted by rotation of the heel member.

Yet another object is to provide a broad 25 wearing surface for a rotatable heel.

Broadly stated the invention comprises means for attaching wearing surfaces 30 releasably to a clamping member permanently attached to the footwear. The invention comprises interchangeable wearing surfaces and cleats permanently attached to the body 35 of the footwear, gripping said surfaces.

More particularly defined the invention consists of a sole and heel plate permanently attached to the upper portion of the body 35 of the boot or shoe and provided with a series of projections adapted to be cleated over. The portions when cleated over are designed to embrace the interchangeable wearing surfaces, an outer leather sole or 40 an interchangeable heel. Again, the interchangeable heel may be attached to an intermediate plate upon which it can readily rotate.

Some embodiments of the present invention 45 are illustrated in the accompanying drawings, wherein—

Figure 1 is the plan of a fixed heel plate, Fig. 2 section of same, Fig. 3 plan of rotating grip plate with projections, Fig. 4 plan of 50 Fig. 3 with projections alternatively turned upward and downward, Fig. 5 side elevation of Fig. 4, Fig. 6 sectional illustration of Figs. 1 and 5 showing interchangeable wearing

heel, Fig. 7 side elevation of boot showing interchangeable wearing heel attached in position, Fig. 8 alternative construction of Fig. 3, Fig. 9 alternative construction of Fig. 1, Fig. 10 side elevation of boot showing interchangeable heel and sole attached to the continuous metal sole plate, Fig. 11 plan of continuous heel and sole plate showing projections, Fig. 12 alternative arrangement of separable heel and sole plate showing projections and method of attachment, Fig. 13 side view of heel plate having depressed center, Fig. 14 alternative arrangement of cleats.

In each of the illustrations similar letters of reference are used to denote similar or corresponding parts wherever they occur.

In the drawings *a* is the fixed heel plate having fastening holes at *b* for the reception of nails, brads or screws. A rotary grip plate is shown at *c*, and may have holes formed therein at *d*, such holes preferably being larger than the holes *b* so that access may be gained to the latter if so desired.

The rotary grip plate has a number of projections *e* formed around its edge, and it may if so desired be furnished with small 80 projections *f* of a substantially similar nature.

The size of the grip plate is such that it is capable of embracing the fixed heel plate, the small projections *f* being turned upward 85 and inward as indicated in Fig. 6 of the drawings, and the plates may be further or alternatively secured together by means of a metal eyelet such as *g* which passes through a central hole in the fixed heel plate and 90 also through a hole in the rotary grip plate, the latter hole being indicated by dotted lines at *h* in Figs. 4 and 8 of the drawings.

The projections *e* are downwardly and inwardly deflected so as to embrace the wearing heel *j* as will be well understood with reference to Fig. 6 of the drawings, a shallow recess being formed at *k* around the circumference of the heel, which is preferably though not necessarily round as will be readily understood.

The heel portions above described may either be manufactured separately or they may be formed as an integral portion of the sole plate *I* illustrated in Fig. 11 of the 105 drawings, the projections *f* being formed in

connection with the sole plate and heel plate substantially as and for the purposes hereinbefore described, the corresponding sole being shown at *m* in Fig. 10 of the drawings, and being of single, double or multiple thickness of leather, rubber or other material.

In Fig. 12 is illustrated the same principles except that the sole plate is reduced to a narrow strip of metal from which the arms *f* protrude for a sufficient distance to enable their extremities to be cleated over on to the sole as indicated by the long and short dots in the illustration, and the heel piece may be either separately formed or may be formed as an integral portion of the sole plate, being connected thereto as indicated by the dotted portion *n* in the same figure. In either case these portions may be secured to the upper or permanent sole of the boot by nails, brads or screws which pass through the holes *b* previously described.

In Fig. 13 is shown a depression at *o* in the heel plate which will enable the revolving plate when placed adjacent thereto to rotate with comparatively little friction, and at *p* in Fig. 9 provision is made for a center pin or eyelet in the permanent plate for affixing purposes which acts as a center, the underneath plate being a permanent fixture as previously described.

Fig. 14 indicates the use of a series of separate cleats fastened by brads or any other convenient means ready for turning over and cleating for the retention of wearing surface.

Where the expression "metal" is used in the foregoing specification any other suitable material may be employed, and the wearing soles can likewise be either of leather or of manufactured substitute material or compositions, the attachment of the soles to the permanent part of the boots being achieved by the means previously stated, or by stitching, rivets or any other device.

This invention is applicable to a considerable range of footwear, both for adults' and children's boots and shoes, and the size and thickness of the various plates may be increased or decreased according to whether the boot is to be used for light or heavy wear.

This invention is also applicable to toe plates consisting of a comparatively small portion of the device such as the front portion which is cut off by the lines *x y* in Figs. 11 and 12 of the drawings.

The method of using the invention will be obvious from the foregoing descriptive matter and the drawings. Where the sole and heel plates are both used the wearing portion is cut to the requisite size of the sole and heel, and is cleated into position, being held by the projections *e*, but where my in-

vention is only applied to the heel plates the fixed heel plate forms a foundation for the rotary grip plate, free rotation being obtained by the fact that the attachment of the two plates is effected by the inturning of the projections *f* as clearly illustrated in Fig. 6, the cleating being sufficient for holding purposes, but not so tight as to interfere with or impede the free rotation of the rotary grip plate. The holder in addition to the various forms and methods of fixing and shape according to the requirements of customers, adapts itself also as one plate. The holder can be cleated over the original sole or heel or nailed thereto, thus firmly adhering to the original sole or heel, also the holder clamps or firmly holds down the false or wearing heel yet allowing it to revolve so as to regularly distribute the worn portion.

What I claim is:—

1. In footwear, the combination of a plate arranged to be fixed to a heel, a lower plate having alternate upwardly and downwardly turned peripheral tangs, the upwardly turned tangs being arranged to embrace the edge of said heel plate and a removable wearing heel member gripped by the downwardly turned tangs of said lower plate.

2. In footwear, the combination of a circular heel plate provided with holes for fixing to the permanent heel of the footwear, a rotary grip plate having alternate upwardly and downwardly turned peripheral tangs, the upwardly turned tangs being arranged to embrace the edge of said heel plate sufficiently tightly for holding purposes but not interfering with the free rotation of the grip plate, and a removable wearing heel gripped by the downwardly turned tangs of said grip plate.

3. In footwear, the combination of a circular heel plate provided with holes for fixing to the permanent heel of the footwear, a rotary grip plate having alternate upwardly and downwardly turned peripheral tangs, the upwardly turned tangs embracing the edge of said heel plate sufficiently tightly for holding purposes but not interfering with the free rotation of the grip plate, a metallic eyelet rotatably connecting said heel plate and grip plate, and a removable wearing heel member gripped by the downwardly turned tangs of said grip plate.

4. A rotary interchangeable heel member for footwear, consisting in the combination of a circular metal plate arranged to be rotatably secured to the permanent heel of the footwear and provided with peripheral downwardly projecting cleats, and a circular interchangeable heel pad encompassed and gripped by said cleats.

5. A rotary interchangeable heel member for footwear, consisting in the combination of a circular metal plate, fastening means arranged to secure said plate to the per-

manent heel of the footwear, a second metal plate having peripheral cleats some upwardly turned to grip said first-named plate and the remainder downwardly turned and 5 a circular interchangeable heel pad encompassed and gripped by said downwardly turned cleats.

In testimony whereof I have signed my name to this specification in the presence of two subscribing witnesses.

FRANZ ERNST WILHELM MÖLLER.
